UNITED STATES PATENT OFFICE

ALLEN DAZEY, OF LOMA LINDA, CALIFORNIA

DISPENSING DEVICE FOR TOOTH-PASTE

Application filed January 27, 1931. Serial No. 511,588.

My invention relates to dispensing pasty or creamy materials from collapsible tubes and relates particularly to devices of this character for dispensing tooth paste efficiently, economically and sanitarily as wanted from the collapsible tubes in which tooth paste is ordinarily sold.

It is the object of my invention to provide a device of the character described which will be inexpensive to construct, readily assembled or taken apart for packing for transportation or for cleaning, will be attractive in appearance, will carry tooth brushes and a water glass and so support the tooth paste tube that its contents may be dispensed downward onto a tooth brush. A further object of my invention is to provide means for yieldingly compressing the tooth paste tube so as to ensure discharge of its contents. A further object is to provide a construction by which the compressed portion of the tooth paste tube will be drawn up into an enclosed portion of the device so as to be out of sight. A further object is to provide means for fastening the device to a wall or other fixed object.

With the objects above indicated and other objects hereinafter described in view, my invention consists of and comprises the construction and combination of elements hereinafter described and claimed.

Figure 1 is a front view of a complete device embodying my invention.

Figure 2 is a side view of the same.

Figure 3 is a top plan view of the same.

Figure 4 is a bottom plan view of the same.

Figure 5 is a horizontal, sectional view on line 5-5 of Figure 6, showing the rollers and operating mechanism.

Figure 6 is a vertical central sectional view on line 6-6 of Figure 3.

Figure 7 is a vertical central sectional view on line 7-7 of Figure 3.

Figure 8 is a bottom plan view of a modified construction.

Figure 9 is a horizontal sectional view on line 9-9 of Figure 10.

Figure 10 is a vertical central sectional view on line 10-10 of Figure 8.

Figure 11 is a vertical central sectional view on line 11-11 of Figure 8.

Figure 12 is a front view of one of the inverted U or horseshoe springs.

In the drawings 1 indicates a horizontal supporting plate having at its rear a downwardly turned portion 2 provided with openings to receive screws 3, 4, or other fastening means by which the device may be secured to a vertical wall or door. One side edge of plate 1 is provided with notches 5 adapted to receive the shanks 35 of tooth brushes, this edge of the plate being turned up as shown at 6 to retain the tooth brushes in vertical position.

The portion of plate 1 opposite the side edge which is provided with notches 5 carries on its upper face an annular dished member 7 which may be integral with or separate from plate 1.

Within the opening of annular plate 7, is arranged a frusto-conical shell or hollow member 8, 9, the portion 8 of which extends upward to form a support for an inverted water glass 10. The dishing of annular plate 7 will receive any drip from a glass inverted on upwardly extending portion 8. The frusto-conical member 8, 9, is formed of sheet metal and is closed at its top by disc 12 and is closed at its bottom by a disc or plate 13 which carries the mechanism for compressing the tooth paste tube 14. The mechanism for this purpose comprises a pair of rollers 16 and 17, preferably corrugated as shown, and means for rotating the rollers to compress between them the tooth paste tube and to feed the compressed portion upward into the frusto-conical member 8, 9, within which it is concealed from view.

The bottom disc or plate 13 is provided with an opening 18 rectangular in shape through which the end of the tooth paste tube is passed to be engaged by the rollers 16 and 17. On the upper face of disc or plate 13 are carried parallel upwardly extending plates 19 and 20, having openings 28 and 29 in them for the shafts 21 and 22, on the mid portions of which rollers 16 and 17 are carried. These plates 19 and 20 may be carried by a ring 23 secured on the upper face of

disc 13 and fitting into the lower end of portion 9 of the frusto-conical member 8, 9, and secured therein by screws 24¹ or other fastening means. Both shafts 21 and 22 terminate at one end within ring 23 while at the other end shaft 22 extends outward beyond the lines of the downwardly extending portion 9 of shell 8, 9, which is provided with an opening 24 for this shaft. At its outer end this shaft is provided with hand wheel 25.

Shafts 21 and 22 are provided with intermeshing gears 26, 27, located between plate 20 and ring 23. The openings 28, 29, in plates 19 and 20 extend to the lower edges of the plates so that in assembling the parts the shafts may be readily put in place before ring 23 is secured to bottom plate 13. Block 30, 31, carried by plate 13 closes openings 28, 29, so as to retain the shafts in place.

For the purpose of pressing rollers 16 and 17 yieldingly together I provide inverted U or horseshoe shaped springs 32, 33, the legs of which are each provided on their insides with notches 34 adapted to receive and form bearings for the end portions of shafts 21, and 22. The legs of these springs 32 and 33 are of such length that when their ends rest upon the upper face of bottom plate 13 the notches 34 will hold the shafts in position above plate 13. The necessity for forming bearings in the parallel plates 19 and 20 is thus obviated, it being necessary only to form the openings 28, 29, of sufficient size to receive the shafts.

Instead of bottom plate 13 with ring 23 and the upwardly extending plates 19 and 20, carried by the ring, I may use the construction shown in Figures 8 to 11, and in which a disc 40 of thin sheet metal takes the place of bottom plate 13 and is secured in place by tabs 41 on the lower end of shell 8, 9, extending through slots in disc 40 and bent over. In this construction upwardly extending plates 42, 43, take the place of plates 19, 20, these plates 42, 43, being integral with connecting piece 44 and secured to disc 40 by tabs 45 extending through slots in the disc and bent over. The plates 42, 43, and connecting piece 44 may be formed of relatively thin sheet metal stiffened as shown by bending their upper edges inward or outward at right angles. These plates 42, 43, have formed in them openings 28, 29, for the shafts 21, 22, but instead of blocks 30, 31, the material of disc 40 at the ends of openings 18 may be bent upward as shown at 46, 47, so that their ends will bear against the shafts 21 and 22. The inverted U shape or horseshoe springs 32, 33, are the same in the modified construction as in the construction shown in Figures 1 to 7. In this construction the sheet metal at the upper ends of openings 28, 29, is bent outward as shown at 48, 49, and the metal at the upper end of 46, 47 is also bent outward as shown at 50, 51, these outwardly bent por-

tions 48, 49, 50, 51 serving to space the gears and the springs away from the thin plates 42, 43.

In the construction shown in Figures 8 to 11 the top plate 52 may be secured to the hollow member 8, 9, by tabs 53 extending through openings in the top plate and bent down.

In the construction shown in Figures 1 to 7, the hollow member 8, 9, is shown as spun or stamped in a single piece though it may be otherwise formed. In the construction shown in Figures 8 to 11, the hollow member may be of thin sheet metal bent into frustoconical form and held in shape by inserting it through the opening in dished member 7 from below and by the tabs which secure the top plate 52 and bottom plate 40 in position.

In assembling the parts in the construction shown in Figures 1 to 7, the shafts 21, 22, with rollers 16, 17, and gears 26, 27, will be placed in openings 28, 29, of plates 19 and 20, and bottom plate 13 so placed on the bottom of ring 23 that blocks 30 and 31, will hold the shafts in openings 28, 29, and soldered or otherwise secured. Springs 32, 33, may then be sprung over the ends of the shafts 21, 22, with their notches 34 engaging the shafts and with the ends of the springs bearing against bottom plate 13. The ring 23 with the bottom plate 13 and the parts assembled as above may then be inserted in the lower end of hollow member 8, 9, shaft 22 entering openings 24, and may be secured by screws 24¹.

In assembling the parts in the construction shown in Figures 8 to 11, shafts 21, 22, should be placed in the openings 28, 29, and bottom plate 40 should be so placed that its upturned portions 46, 47, will bear against the shafts and the tabs on the lower edges of plates 42, 43, 44, will extend through openings in plate 40 so as to be turned down to hold plates 42, 43, 44, in position. Springs 32, 33, may then be caused to embrace the end portions of shafts 21, 22, and plate 40 may then be secured in position by means of tabs 41.

It will, of course, be understood that I do not desire to be limited to the precise construction shown and described, nor do I desire to be limited to the use of the construction described and claimed for compressing tooth paste tubes, as the device may obviously be used for compressing other tubes.

Having thus described my invention, what I claim is:

1. In a dispensing device for the purpose described, a horizontal base plate provided with means for securing it to a vertical surface, an annular member carried by the base plate on its upper face, a hollow member secured in the annular member extending above and below the base plate and means carried by the portion of the hollow member below

the base plate for compressing a collapsible tube so arranged as to feed the collapsed portion of the tube upward into said hollow member.

2. In a dispensing device for the purpose described, a horizontal base plate, an annular member carried by the base plate on its upper face, a hollow member carried by the base plate and extending above and below it concentric with the annular plate, compression rollers carried by the portion of the hollow member below the base plate, adapted to compress a collapsible tube and to feed the collapsed portion of the tube upward into said hollow member.

3. In a dispensing device for the purpose described, a horizontal base plate, an annular member carried by the base plate on its upper face, a hollow member carried by the base plate extending above and below it concentric with the annular plate, compression rollers carried by the portion of the hollow member below the base plate adapted to compress a collapsible tube and to feed the collapsed portion of the tube upward through the hollow member, and means for yieldingly pressing the rollers together.

4. In a dispensing device for the purpose described, a horizontal base plate, an annular member carried by the base plate on its upper face, a hollow member carried by the base plate extending above and below it concentric with the annular plate, compression rollers carried by the portion of the hollow member below the base plate adapted to compress a collapsible tube, and to feed the compressed portions of the tube upward into said hollow member and means for yieldingly pressing the rollers together consisting of **U** shaped springs having their legs extending downward within the hollow member and bearing against the shafts of the rollers.

5. In a dispensing device for the purpose described, a horizontal base plate, an annular member carried by the base plate on its upper face, a hollow member carried by the base plate extending downward therefrom concentric with the annular member, parallel bars carried by said downwardly extending hollow member on opposite sides of its centre so arranged as to leave spaces between each of said bars and the wall of said downwardly extending hollow member, and parallel shafts journalled in said bars carrying between the bars compression rollers adapted to compress a collapsible tube.

6. In a dispensing device for the purpose described a horizontal base plate, an annular member carried by the base plate on its upper face, a hollow member carried by the base plate extending downward therefrom concentric with the annular member, parallel bars carried by said downwardly extending hollow member on opposite sides of its centre so arranged as to leave spaces between each of

said bars and the wall of said downwardly extending hollow member, parallel shafts journalled in said bars carrying between the bars compression rollers adapted to compress a collapsible tube and having intermeshing gears in the spaces between the bars and the wall of the downwardly extending member.

7. In a dispensing device for the purpose described a horizontal base plate, an annular member carried by the base plate on its upper face, a hollow member carried by the base plate extending downward therefrom concentric with the annular member, parallel bars carried by said downwardly extending hollow member on opposite sides of its centre so arranged as to leave space between each of said bars and the wall of said downwardly extending hollow member, parallel shafts journalled in said bars carrying between the bars compression rollers adapted to compress a collapsible tube and having intermeshing gears in the spaces between the bars and the wall of the downwardly extending member.

8. In a dispensing device for the purpose described a horizontal base plate, an annular member carried by the base plate on its upper face, a hollow member carried by the base plate extending downward therefrom concentric with the annular member, parallel bars carried by said downwardly extending hollow member on opposite sides of its centre so arranged as to leave space between each of said bars and the wall of said downwardly extending hollow member, parallel shafts journalled in said bars carrying between the bars compression rollers adapted to compress a collapsible tube and having intermeshing gears in the spaces between the bars and the wall of the downwardly extending member, and compression springs extending into said spaces between the bars and the wall of the downwardly extending member.

9. In a dispensing device for the purpose described a horizontal base plate, an annular member carried by the base plate on its upper face, a hollow member carried by the base plate extending downward therefrom concentric with the annular member, parallel bars carried by said downwardly extending hollow member on opposite sides of its centre so arranged as to leave spaces between each of said bars and the wall of said downwardly extending hollow member, parallel shafts journalled in said bars carrying between the bars compression rollers adapted to compress a collapsible tube, and notches extending upward from the lower edges of the bars to receive the shafts.

10. In a dispensing device for the purpose described, means for compressing a collapsible tube comprising a plate having an opening therein to receive the end of the collapsible tube, a pair of rollers opposite said opening, shafts carrying said rollers and means for supporting said shafts in position consisting of inverted **U** shaped springs provided on the inside of their legs with notches adapted to engage said shafts.

In testimony whereof, I hereunto affix my signature.

ALLEN DAZEY. 120
